UNITED STATES PATENT OFFICE.

CHARLES M. AMSDEN, OF WOOSTER, OHIO.

SLED.

SPECIFICATION forming part of Letters Patent No. 253,332, dated February 7, 1882.

Application filed October 21, 1881. (No model.)

To all whom it may concern:

Be it known that I, CHARLES M. AMSDEN, of Wooster, Wayne county, Ohio, have invented a new and useful Improvement in Sleds and Sleighs, of which the following is a specification.

The invention consists in combining with the ordinary cross-bars, side rails, and seat-board a metallic frame constructed as hereinabove described.

Reference is to be had to the accompanying drawings, in which similar letters of reference represent corresponding parts in all the figures.

In the drawings, Figure 1 is a side elevation of a sled of my improved construction. Fig. 2 is a transverse section of the sled, and Fig. 3 is a cross-section of the sled as constructed with wooden posts or braces.

Referring to Figs. 1 and 2, A A are the runners. B B are the posts or braces connected to the runners and fitted with cross-bars *a* at their upper ends, on which the longitudinal side rails, *b*, and seat-board *c* are secured.

The runners A are of metal rolled in T form, thereby forming a combined iron and runner, the head portion *d* being the iron proper, and the flange *e* serving as a stiffening-rib on the inner side. The outer surface of the irons *d* are rounded in usual form, or they may be flat.

The posts B are formed of metal bars *ff'*, riveted together and to the rib *e* of the runner, the inner bars, *f'*, at each side being in one

piece, arched to form a cross-brace and a support for the cross-bars *a*.

When it is preferred to use wooden posts 35 they are made, as shown in Fig. 3, with slots or mortises in their lower ends to set over the ribs *e* of the runners, and are framed into the cross-bars at their upper ends.

The sled constructed as described is light 40 and strong, and in appearance is much more handsome than the ordinary wooden sled. The parts can be made almost entirely by machinery, and but little hand-work is required to complete the sled.

The T-iron runners may be used on sleighs 45 as well as on hand-sleds. I do not limit myself in that respect.

I am aware that it is not new to use T-iron runners or wooden posts connected by an arch 50 and braced by metallic straps; but

What I claim is—

In a sled, the combination, with the cross-bars *a*, side rails, *b*, and seat-board *c*, of the metallic arches *f'*, the side bars, *f*, turned horizontally outward at the top, and the T-iron runners A, the said arch-bars and side bars being riveted together and to the rib *e* of the runners, as shown and described. 55

CHARLES MASSENA AMSDEN.
